INTERCOOLED COMPRESSING APPARATUS

Robert C. Allen, Wauwatosa, Clarence E. Kenney, West Allis, and William F. Wilson, Wauwatosa, Wis., assignors to Allis-Chalmers Manufacturing Company, Milwaukee, Wis., a corporation of Delaware

Application July 24, 1944, Serial No. 546,358

11 Claims. (Cl. 230—209)

This invention relates to multistage intercooled compressing apparatus of the type particularly adapted for use in continuous combustion gas turbine systems employing regenerative heating of the compressed air prior to its introduction into the combustion chamber of the system and has for its primary object the provision of an improved compressor and intercooling structure embodying novel correlations of features removably mounting separable intercooler sections between adjacent axially spaced compressor sections or stages thereby affording a compact, durable construction which can be readily manufactured, installed and serviced with a minimum of time, skill and effort.

The construction of apparatus embodying the invention will become readily apparent as the disclosure progresses and particularly points out additional objects, advantages and features of construction considered of special importance and of general application although illustrated and described as applied to an axial type compressor embodying longitudinally spaced compressing portions or sections.

Accordingly, the invention may be considered as consisting of the various combinations of elements and parts constructed and/or correlated as is more fully set forth in the appended claims and in the detailed description, reference being had to the accompanying drawings, in which:

Fig. 1 is a longitudinal vertical section through an intercooled compressing apparatus illustrating an embodiment of the invention;

Fig. 2 is a transverse section taken on line II—II of Fig. 1;

Fig. 3 is a plan view of the intercooler structure;

Fig. 4 is a view similar to Fig. 3 with the intercooler sections removed, parts broken away adjacent the bearing support;

Fig. 5 is a side view of structure shown in Fig. 4 with portions of the housing broken away to better show the arrangement of parts; and

Fig. 6 is a section taken on line VI—VI of Fig. 5.

Referring to Figs. 1 and 2, it is seen that the invention may be applied to an axial compressor including a low pressure section or rotor element 1 having oppositely extending reduced shaft portions 2 and 3, a high pressure section or rotor element 4 having oppositely extending reduced shaft portions 6 and 7 with the portion 6 united with the adjacent alined end of the shaft portion 3 of section 1, and a horizontally split, separable casing structure 8 which may be supported on any suitable structure by means of axially spaced projections 9 and which carries axially alined bearings 11, 12 and 13 rotatably supporting shaft portions 2, 6 and 7, respectively; the inlet end of casing 8 preferably including a separable section 14 as indicated. However, the manner in which

bearings 11 and 13 are supported by the end portions of casing 8 is not of particular importance and a further description in this connection is deemed unnecessary for a complete understanding of the invention.

The intermediate portion 16 of casing 8, that is the portion enclosing the united shaft portions 3 and 6, is enlarged and provided with a pair of oppositely disposed openings, in this case top and bottom openings 17 and 18, respectively, adapted to be closed by cover members 19 and 21 removably secured in any suitable manner to the casing flanges 22 and 23 surrounding the openings 17 and 18. In this connection, it is preferable, although not necessary in order to provide a simplified construction, that the enlarged portion 16 appear as a rectangular structure having rectangular top and bottom openings (see Figs. 2—5 inclusive) and that the enlarged portion be integrally merged with the cylindrical portions of the casing surrounding the blade carrying portions of compressor sections 1 and 4.

The lower portion of the conventional, longitudinally split bearing structure 12 (see Figs. 1, 4, 5 and 6) is supported at its opposite ends by pairs of oppositely extending laterally spaced integral projections 24 and 26 mounted on underlying pairs of pads 27 and 28 carried by the lower half of inner coaxial casing parts 29 and 31 which are in turn carried by the outer surrounding portion of the main casing by means of struts or the like 32 and 33, respectively; the parts 29 and 31 also coacting with the surrounding portion of the main casing and with the adjacent bladed portions of rotors 1 and 4 to form coaxial discharge and inlet passages 25 and 30, respectively. Opposite ends of the shell structure of bearing 12 are provided with conventional labyrinth shaft seals 34 to prevent air from flowing along shaft portion 6 and entering the annular spaces 36. In addition, the upper and lower portions of the bearing shell are provided with openings 37 for discharging air from the spaces 36 and with oppositely projecting radial breathing tubes 38 and 39 which enclose portions of the bearing casing including the openings 37 and extend outward through the openings 17 and 18 in the enlarged portion 16 of casing 8 thereby placing the spaces 36 in continuous communication with the atmosphere. Bearing 12 is continuously supplied with lubricant by means of a pair of concentric oil supply and return conduits 41 and 42 which extend through tube 39 and into the bearing structure proper as is clearly indicated in Figs. 1 and 2.

The cover members 19 and 21 may be interchangeably constructed to include similar tube receiving openings 43 and a pair of similar intercooler ring-forming quadrant-shaped segments or sections 44 each comprising as best shown in Figs. 1, 2 and 3, in which like numbers are used

to designate the same or corresponding parts, a plurality of air conducting tubes 47 supported in parallel relation by a pair of axially spaced end tube sheets 48 and 49 and by an intermediate baffle sheet 51 and an enclosing structure including tube sheets 48 and 49, side walls 52 and 53 uniting the vertical and horizontal edges, respectively, of tube sheet 48 with the corresponding edges of baffle sheet 51 and tube sheet 49, an inner wall 54 uniting the inner arcuate edge of tube sheet 48 with the corresponding edge of tube sheet 49, and an outer wall 56 uniting the outer arcuate edge of tube sheet 48 with the corresponding edges of baffle sheet 51 and tube sheet 49. Baffle sheet 51 terminates short of the inner wall 54 and thereby divides the interior of the enclosure containing tubes 47 into a pair of communicating chambers 45 and 46. The upstream and downstream ends of walls 52, 53, 54 and 56 extend beyond the tube sheets 48, 49 and 20 abut or otherwise engage the adjacent ends of the inner casing portions 29, 31 and surrounding projections 57, 58 on the interior of the main casing to form intercooler inlet and outlet passages 59 and 61, respectively; passage 59 forming a rearward continuation of low pressure section discharge passage 25 and passage 61 forming a forward extension of high pressure section inlet passage 30 as is clearly indicated in Fig. 1.

In this connection, it should be noted that the outer wall 56 of each quadrant segment 44 is provided with a pair of spaced outwardly extending conduits 62 (one conduit communicates with chamber 45 and the other with chamber 46) which project through and support the segment 35 on the associated cover member in any suitable sealed manner such as by welds 63 and that when a pair of segments are properly so assembled the vertical walls 52 on adjacent segments are spaced apart to receive a tube 38 or 39 therebetween (see Figs. 2 and 3). In addition, it should be noted that the upstream edge portions of walls 52 are convergently bent to abut each other and form a rounded deflecting portion 64 for directing the air or other gas issuing from low pressure section 1 away from the space between walls 52 and into the passages 59 communicating with the upstream ends of tubes 47. It should also be noted that the correlation of parts thus far described is such that an assembly comprising a cover member and a pair of quadrant segments may be removed as a unit from enlarged portion 16 of casing 8 simply by loosening or removing the seal 66 surrounding the outer end of tube 38 or 39, by removing the bolts or other means (not shown) securing the cover member to the coacting casing flange 22 or 23 and then withdrawing the unit. After the assembly has been inspected and/or serviced as required, it may be readily positioned as shown and the cover member again secured to the coacting flange 22 or 23 thus placing the unit in condition for operation.

Stated differently, the casing structure 8 is provided with circumferentially spaced intermediate parts (cover members 19, 21) which are severally removable to expose the bearing 12 and the connection between shaft portions 3 and 6 for removing and/or servicing the bearing and/or the shaft coupling connection; an intercooling structure or at least one intercooler section (quadrant segment 44) is mounted on the removable casing part for insertion and removal therewith to and from a position in which the intercooler sections are disposed between the opposed outlet and inlet ends of the low and high pressure compressing

elements in surrounding coaxial relation with respect to the shaft portions 3, 6 and bearing 12; each intercooling structure or intercooler section providing at least one passage for conducting compressed gas issuing from the discharge or outlet of the low pressure element to the inlet of the high pressure element; and the bearing 12 is provided with at least one breathing conductor (tubes 38, 39) which project outward through the intercooling structure or the ring of intercooler sections and through the removable casing part. Whether it is necessary for the breathing conductor to project through the intercooling structure or ring of intercooler section and/or through the removable casing part or cover member is of course dependent upon the particular construction and arrangement of such parts.

In operation, baffle sheet 51 compels the cooling gas or liquid entering chamber 46 through one conduit 62 to flow inward around the portion of the tubes 47 contained therein, around the inner end of baffle sheet 51 and into chamber 45, outward around the portion of the tubes 47 contained therein and then out of chamber 45 through the other conduit 62. The compressed gas leaves low pressure section 1 through annular discharge passage 25 and flows through passages 59, through the tubes 47 and through passages 61 from which it enters the annular inlet passage 30 of high pressure section 4; each quadrant segment providing a pair of passages 59 and 61 interconnected by a group of tubes 47 disposed in substantially parallel relation with respect to the common axis of the rotor elements 1 and 4. And consequently, the herein disclosed construction and arrangement of the intercooling structures or sections afford an approximately straight-through passage or passages directly connecting the discharge of the low pressure section 1 with the inlet of the high pressure section 4. The temperature of the compressed gas passing through the groups of tubes 47 is materially reduced by the flow of a cooling gas or liquid around the tubes as hereinbefore described. Whether the cooling medium flowing through chambers 45 and 46 of the intercooling structure herein shown is made to pass around the inner end of baffle sheet 51 in counterflow relation to the gas flowing through tubes 47 is purely a matter of choice and may be operated as desired by connecting the appropriate conduit 62 with a suitable source of cooling fluid (not shown). In this connection, it is also immaterial whether the intercooling structures or sections are of the type herein shown and described for purposes of illustration as the only requisite in this respect is that the construction be such as will permit mounting same on the removable casing part or parts for insertion and removal therewith in the manner previously indicated.

With respect to the operation of the apparatus herein disclosed, it should be noted (see Fig. 1) that some of the compressed gas in passing from low pressure section 1 to high pressure section 4 is likely to enter the space 67 surrounding the intercooling structure formed by quadrant segments 44 and to also enter the inner space 68 surrounding shaft portions 3, 6 and bearing 12, that the compressed gas in space 67 is prevented from escaping by engagement of the cover members 19 and 21 with flanges 22 and 23 and by the connections 63 and seals 66 engaging conduits 62 and tubes 38, 39, respectively, and that if any compressed gas in space 68 flows along shaft portion 8 past the labyrinth seals 34 and into the

spaces 36, such gas will not aerate and destroy the lubricating properties of the oil flowing through the bearing 12 as it freely passes to atmosphere through the breather conductor comprising openings 37 and tubes 38, 39. In addition, it should also be noted that tubes 38, 39 provide access to the bearing 12 for taking temperature readings, soundings and the like during operation of the apparatus. Moreover, if bearing trouble should develop, the bearing and/or the connection or coupling between shaft portions 3 and 6 can be readily serviced or if necessary removed and serviced simply by removing one or both cover members and the intercooling structures carried thereby. Furthermore, it should be understood that although it is preferable to provide the casing structure 8 with an enlarged intermediate portion 16 of rectangular cross-section having two diametrically opposed rectangular openings and to close such openings by cover members each carrying a pair of intercooler forming quadrant segments, the number and shape of the openings and cover members and the shape, number and construction of the intercooler segments or sections carried by each cover member as well as the construction of the casing proper may be varied as desired to meet particular requirement.

The invention is generally applicable to all types of compressing apparatus embodying spaced series flow connected low and high pressure compressing sections, and although the invention has been illustrated and described as applied to an axial type compressor having an integrally united casing structure for the low and high pressure sections, it should be further understood that it is not intended to limit the invention to the details of such a construction as various modifications within the scope of the appended claims may occur to persons skilled in the art.

It is claimed and desired to secure by Letters Patent:

1. An intercooled compressing apparatus comprising low and high pressure blade carrying rotor elements operatively connected in spaced axially aligned relation with the discharge end of the low pressure element coaxially opposing the inlet end of the high pressure element, a casing structure enclosing said elements and including severally removable intermediate parts disposed between the discharge end of the low pressure element and the inlet end of the high pressure element, and at least one intercooling structure carried by each of said parts for insertion and removal therewith to and from a position wherein in said intercooling structures are disposed between said discharge and inlet ends of the elements in generally symmetrical relation with respect to the common axis of said elements, said intercooling structures providing one or more approximately straight-through passages directly connecting the discharge of the low pressure element with the inlet of the high pressure element.

2. An intercooled compressing apparatus comprising low and high pressure blade carrying rotor elements having an intermediate shaft portion connecting same in spaced axially aligned relation with the discharge end of the low pressure element coaxially opposing the inlet end of the high pressure element, a casing structure enclosing said elements and shaft portion and including intermediate parts disposed between the discharge end of the low pressure element and the inlet end of the high pressure element and being

severally removable to expose said shaft portion, and at least one intercooling structure carried by each of said parts for insertion and removal therewith to and from a position wherein in said intercooling structures are disposed between said discharge and inlet ends of the elements in generally symmetrical relation with respect to said shaft portion, said intercooling structures providing one or more approximately straight-through passages directly connecting the discharge of the low pressure element with the inlet of the high pressure element.

3. An intercooled compressing apparatus comprising low and high pressure blade carrying rotor elements having an intermediate shaft portion connecting same in spaced coaxial relation with the discharge end of the low pressure element opposing the inlet end of the high pressure element, a casing structure enclosing said elements and said shaft portion, a bearing for said shaft portion carried by axially spaced inner portions of said casing, said casing including intermediate parts severally removable to expose said bearing for removing and/or servicing same, and at least one intercooler section mounted on each of said parts for insertion and removal therewith to and from a position in which said sections are disposed between the discharge and inlet ends of said elements in surrounding relation with respect to said bearing, said intercooler sections each providing at least one passage for conducting compressed gas issuing from the discharge of the low pressure element to the inlet of the high pressure element.

35 4. An intercooled compressing apparatus comprising low and high pressure blade carrying rotor elements having opposed shaft portions connecting same in spaced coaxial relation with the discharge end of the low pressure element opposing the inlet end of the high pressure element, a casing structure enclosing said elements and shaft portions and including an intermediate part removable to expose the connection between said shaft portions, and an intercooling structure mounted on said part for insertion and removal therewith to and from a position between the discharge and inlet ends of said elements, said intercooling structure providing at least one passage for conducting compressed gas issuing from the discharge of the low pressure element to the inlet of the high pressure element.

5. An intercooled compressing apparatus comprising low and high pressure blade carrying rotor elements having opposed shaft portions connecting same in spaced coaxial relation with the discharge end of the low pressure element opposing the inlet end of the high pressure element, a casing structure enclosing said elements and shaft portions and including intermediate parts severally removable to expose the connection between said shaft portions, and at least one intercooler section mounted on each of said parts for insertion and removal therewith to and from a position in which said sections are disposed between the discharge and inlet ends of said elements in surrounding relation with respect to said connection, said intercooler sections each providing at least one passage for conducting compressed gas issuing from the discharge of the low pressure element to the inlet of the high pressure element.

6. An intercooled compressing apparatus comprising low and high pressure blade carrying rotor elements having an intermediate shaft portion connecting same in spaced coaxial relation with

the discharge end of the low pressure element opposing the inlet end of the high pressure element, a casing structure enclosing said elements and shaft portions, a bearing for said shaft portion carried by inner axially spaced portions of said casing structure, said bearing including a shell structure providing a chamber sealed against the admission of compressed gas thereto and a conductor projecting outwardly through the casing and placing said chamber in continuous communication with the atmosphere, said casing structure including an intermediate part removable to expose said bearing, and a gas intercooling structure mounted on said part for insertion and removal therewith to and from a position between the discharge and inlet ends of said elements, said intercooling structure providing at least one passage for conducting compressed gas issuing from the discharge of the low pressure element to the inlet of the high pressure element.

7. An intercooled compressing apparatus comprising low and high pressure blade carrying rotor elements having an intermediate shaft portion connecting same in spaced coaxial relation with the discharge end of the low pressure element opposing the inlet end of the high pressure element, a casing structure enclosing said elements and shaft portions, a bearing for said shaft portion carried by inner axially spaced portions of said casing structure, said casing structure including an intermediate part removable to expose said bearing, said bearing including a shell structure providing a chamber for receiving compressed gas leaking into the bearing, a fixed breathing conductor projecting outwardly through said removable casing part and placing said chamber in continuous communication with the atmosphere, and a gas intercooling structure mounted on said part for insertion and removable therewith to and from a position in which the intercooling structure is disposed between the discharge and inlet ends of said elements in partially surrounding relation with respect to said conductor, said intercooling structure providing at least one passage for conducting compressed gas issuing from the discharge of the low pressure element to the inlet of the high pressure element.

8. An intercooled compressing apparatus comprising low and high pressure blade carrying rotor elements having an intermediate shaft portion connecting same in spaced coaxial relation with the discharge end of the low pressure element opposing the inlet end of the high pressure element, a casing structure enclosing said elements and shaft portions, a bearing for said shaft portion carried by inner axially spaced portions of said casing structure, said bearing including a shell structure providing a chamber for receiving compressed gas leaking into the bearing, said casing structure including an intermediate part removable to expose said bearing and the supports therefor, a gas intercooling structure mounted on said part for insertion and removal therewith to and from a position between the discharge and inlet ends of said elements, said intercooling structure providing at least one passage for conducting compressed gas issuing from the discharge of the low pressure element to the inlet of the high pressure element, and a breathing conductor communicating with said chamber and projecting outwardly

through said intercooling structure and through said removable casing part.

9. An intercooled compressing apparatus comprising low and high pressure blade carrying rotor elements having an intermediate shaft portion connecting same in spaced coaxial relation with the discharge end of the low pressure element opposing the inlet end of the high pressure element, a casing structure enclosing said elements and shaft portions, a bearing for said shaft portion carried by inner portions of said casing structure, said casing structure including circumferentially spaced intermediate parts severally removable to expose said bearing and the supports therefor, and a separate ring-forming intercooler section mounted on each of said parts for insertion and removal therewith to and from a position in which said intercooler sections are disposed between the outlet and inlet ends of said elements in surrounding coaxial relation with respect to said bearing, said intercooler sections each providing at least one passage for conducting compressed gas issuing from the discharge of the low pressure element to the inlet of the high pressure element, and a breathing conductor for said bearing projecting outwardly through said ring of intercooler sections and through one of said severally removable casing parts.

10. An intercooled compressing apparatus comprising low and high pressure blade carrying rotor elements having opposed shaft portions connecting same in spaced coaxial relation with the discharge end of the low pressure element opposing the inlet end of the high pressure element, a casing structure enclosing said elements and shaft portions, said casing structure including circumferentially spaced intermediate parts severally removable to expose the junction of said shaft portions, and at least one ring-forming intercooler section mounted on each of said parts for insertion and removal therewith to and from a position in which said intercooler sections are disposed between the outlet and inlet ends of said elements in surrounding coaxial relation with respect to said shaft portions, said intercooler sections each providing at least one passage for conducting compressed gas issuing from the discharge of the low pressure element to the inlet of the high pressure element.

11. An intercooled compressing apparatus comprising low and high pressure blade carrying rotor elements operatively connected in spaced axially aligned relation with the discharge end of the low pressure element coaxially opposing the inlet end of the high pressure element, a casing structure enclosing said elements and including a removable intermediate part disposed between the discharge end of the low pressure element and the inlet end of the high pressure element, and an intercooling structure mounted on said part for insertion and removal therewith to and from a position between and in generally end-opposed relation with respect with the coaxially opposed discharge and inlet ends of said elements, said intercooling structure providing at least one approximately straight-through passage directly connecting the discharge of the low pressure element with the inlet of the high pressure element.
